UNITED STATES PATENT OFFICE

158,186

DATE STAMP CASING

Jack Fairchild Fleming, Scarsdale, N. Y., assignor
to Sterling Plastics Company, Union, N. J., a
corporation of New Jersey

Application November 5, 1948, Serial No. 149,487

Term of patent 7 years

(Cl. D64—10)

To all whom it may concern:

Be it known that I, Jack Fairchild Fleming, a citizen of the United States of America, and a resident of Scarsdale, in the county of Westchester and State of New York, have invented a new, original, and ornamental Design for a Date Stamp Casing, of which the following is a specification, reference being had to the accompanying drawing, forming a part thereof.

Figure 1 is a top plan view of a date stamp casing, showing my new design.

Figure 2 is a front elevational view of the date stamp casing.

Figure 3 is a side elevational view thereof, the other side being the same.

Figure 4 is a rear elevational view of the date stamp casing, and

Figure 5 is a bottom plan view of the date stamp casing.

The design is characterized by the parts that are shown by solid lines, the broken lines indicating rubber stamp tapes.

I claim:

The ornamental design for a date stamp casing, as shown and described.

JACK FAIRCHILD FLEMING.
